United States Patent Office

Des. 196,100
Patented Aug. 27, 1963

196,100

SEWER CLEANER

Charles J. O'Neill, Mendota, Ill., assignor to Conco Engineering Works, Inc., Mendota, Ill., a corporation of Illinois

Filed Aug. 22, 1961, Ser. No. 66,454

Term of patent 14 years

(Cl. D9—2)

FIGURE 1 is a front perspective view of the sewer cleaner embodying my novel design.

FIG. 2 is a front elevation thereof, viewed in perspective from a position above the horizontal axis.

FIG. 3 is a rear elevation thereof.

FIG. 4 is a side elevation thereof.

I claim:

The ornamental design for a sewer cleaner, as shown.
